(57) **CLAIM**

The ornamental design for an combined outdoor power post and outdoor power post cover, as shown and described.

DESCRIPTION

FIG. 1 is a perspective view of an combined outdoor power post and outdoor power post cover according to the present design;

FIG. 2 is a front view of the combined outdoor power post and outdoor power post cover of FIG. 1;

FIG. 3 is a rear view of the combined outdoor power post and outdoor power post cover of FIG. 1;

FIG. 4 is a left side view of the combined outdoor power post and outdoor power post cover of FIG. 1;

FIG. 5 is a right side view of the combined outdoor power post and outdoor power post cover of FIG. 1;

FIG. 6 is a top view of the combined outdoor power post and outdoor power post of FIG. 1; and,

FIG. 7 is a bottom view of the combined outdoor power post and outdoor power post cover of FIG. 1.

In the drawings, the broken lines are for the purpose of illustrating portions of the combined outdoor power post and outdoor power post cover that forms no part of the claimed design.

1 Claim, 6 Drawing Sheets
